UNITED STATES PATENT OFFICE.

JAMES F. ROBERTS, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

ROTOR.

Application filed April 1, 1922. Serial No. 548,603.

To all whom it may concern:

Be it known that JAMES F. ROBERTS, a citizen of the United States, residing at Milwaukee, in the county of Milwaukee and State of Wisconsin, has invented a certain new and useful Improvement in Rotors, of which the following is a specification.

This invention relates in general to improvements in the art of converting energy from one form into another with the aid of a rotary element, and relates more specifically to improvements in the construction and operation of energy converting rotors for fluid energy translating mechanisms such as turbines, pumps, propellers and the like.

A general object of the invention is to provide an improved energy converting rotor which is simple in construction and efficient in operation. It has been found that greatly superior results in operation follow a simple recession of the discharge edge of a rotor blade at the working face, and such structure comprises a feature of the present invention.

Some of the more specific objects of the invention are as follows:—

To provide improvements in the construction of energy converting rotors which are operable at best efficiency at relatively high speeds.

To provide a rotor of the type wherein the flow of fluid at the inlet and discharge is axially directed, and which during normal operation has relatively large quantities of fluid passing therethrough with a whirling motion.

To provide an improved fluid operated turbine rotor structure especially applicable to hydraulic and elastic fluid turbines.

To provide a hydraulic turbine rotor which is operable under relatively low heads to produce relatively high specific or characteristic speeds.

To provide an improved hydraulic rotor of the Nagler type illustrated and described in Volume 41, Number 12 of Mechanical Engineering.

To provide a hydraulic turbine rotor which is extremely simple and compact in construction, in which the wetted surface is reduced to a minimum, and which is relatively efficient in operation.

These and other objects and advantages of the present invention will be apparent from the following specification.

A clear conception of several embodiments of the invention and of the operation of devices constructed in accordance therewith, may be had by referring to the drawing accompanying and forming a part of this specification, in which like reference characters designate the same or similar parts in the several views.

Fig. 1 is a plan view of an improved axial flow hydraulic rotor.

Fig. 2 is a side elevation of the improved hydraulic rotor.

Fig. 3 is an enlarged transverse section through one of the rotor vanes, the section being taken along the line III—III of Fig. 1, looking toward the rotor hub.

Fig. 4 is a transverse section through several elastic fluid turbine blades of the reaction or Parsons type, showing the present invention applied thereto.

The improved hydraulic rotor illustrated in Figs. 1, 2 and 3 is of the high speed axial flow type and comprises a series of four blades or vanes 2 of dovetail formation, having their inner ends rigidly attached to a hub 3 and having free outer ends, that is, having no rim or other means connecting the outer extremities of the successive vanes. The main shaft 4 is rigidly attached to and projects away from one end of the hub 3, and the opposite end of the hub 3 may be provided with a hub cap 8 or with a suitable thrust bearing. The area of the blades or vanes 2 when projected upon a plane perpendicular to the axis of the rotor shaft 4, or as viewed in the direction of flow of the fluid, is substantially less than the area of the annulus located between the circles which bound the ends of the vanes, the percentage of vane area with reference to the total area of the fluid passage defined by this annulus, varying throughout a considerable range with variations in characteristics of the units.

Each of the rotor vanes 2 is bounded by surfaces or faces 5, 6, the faces 5 being the working faces against which the operating fluid coacts. The trailing or discharge edge of each of the vanes 2 is provided with a chamfer or bevel 7 which produces a surface intersecting the working face 5 and which in the type shown is viewable from the fluid inlet side of the rotor and in the direction of rotation of the vane as indicated in Fig. 1. In actual practice, the sur-

face of the vane is preferably rounded off at the intersection of the faces 5 and the chamfers 7, to produce a relatively smooth guiding surface. While this chamfer 7 in 5 the specific rotor illustrated, has been formed by removal of a portion of the discharge edge of the vane 2, as indicated in Fig. 3, it will be obvious that the recession may also be produced by merely distorting or otherwise forming the discharge edge of the vane 10 to produce a beveled surface 7 intersecting the working surface 5.

The invention may be applied to steam or gas turbine blading of any type and in 15 Fig. 4 is illustrated as being applied to steam turbine blading of the reaction or Parsons type. The turbine blades 12 are attached to a suitable support 13 in any well known manner, each of these blades being 20 bounded by oppositely disposed surfaces or faces 15, 16, of which the faces 15 are working faces. The discharge edge of the working face 15 of each of the blades 12 is provided with a chamfer 17 which intersects 25 the working face and which is viewable from the fluid inlet side of the rotor and in the direction of rotation of the blades 12, as indicated in the drawing.

During normal operation of the rotor 30 shown in Figs. 1 and 2, as a hydraulic turbine, the water is admitted to the inlet side of the rotor in an axial direction and with a decided whirling component in the direction of rotation of the rotor. As the 35 axially advancing whirling stream of liquid engages the working faces 5 of the vanes 2, rotation is imparted to the rotor and to the main shaft 4. During its passage through the rotor, the water advances along the 40 working faces 5 and the chamfered discharge edges, successively, the stream of liquid being discharged from the rotor in an axially advancing direction. The discharged fluid may have considerable 45 residual whirling motion, and may have axial flow only, that is, threads of flow proceeding at a constant distance from the axis. Upon leaving the rotor, the whirl and velocity 50 energy of the water is preferably converted into pressure energy with the aid of a decelerator or draft tube. While this chamfer may be contrary to the usual theory applied to the design of blading and cannot be satisfactorily explained, it has been found 55 to have an astonishing result in improving the operation.

A rotor of this general type has been found to produce relatively high specific or 60 characteristic speeds and high efficiency, when operating under relatively low hydraulic heads. It has also been found that by providing chamfered or beveled discharge edges as shown in Figs. 1, 2 and 3, the specific or characteristic speed may be 65 considerably increased. Such chamfering

or beveling of the discharge edges of the vanes probably by increasing the quantity of water passing through, also produces increased energy conversion appearing as torque in the rotating shaft 4 and somewhat 70 increases the efficiency of the unit over that of units having the chamfer omitted.

During normal operation of the elastic fluid turbine illustrated in Fig. 4, the steam or other elastic fluid is admitted to the inlet 75 edges of the blades 12 as one or more axially advancing whirling streams. These streams of elastic fluid impinge against and travel along the working faces 15 of the blades 12, eventually leaving these working faces and 80 coacting with the chamfers 17. The fluid delivered from the vanes 12 may pass either to a set of stationary guide vanes or to a condenser in the usual manner.

It will be noted that the rotors illustrated 85 are exceedingly simple and compact in construction, and that the chamfers 7, 17 provide locally constricted working passages between the successive vanes 2, 12. The specific shape of the rotor vanes may be 90 varied to produce the desired results sought for in various installations. In the hydraulic turbine rotor the wetted surface is reduced to a minimum by eliminating the outer rim, by making the hub 3 of relatively 95 small diameter, and by utilizing axial advancement of the fluid through the rotor. The provision of the chamfer 7, 17 does not materially increase the cost of construction 100 of these rotors and enables attainment of higher characteristic or specific speeds, increased energy conversion, and maximum efficiency.

It will also be obvious that the invention is readily applicable to rotary energy converting machines of other types, such as pumps and propellers, but that the 105 chamfers 7, 17 must be located at the discharge edge of the working face of the vane. Although illustrated herein as specifically applied to rotors of the axial flow type, it 110 will be obvious that the invention may be applied to other types of rotors, such as radial inward or outward or mixed flow rotors.

It should be understood that it is not 115 desired to limit the invention to the exact details of construction and of operation herein shown and described, for various modifications within the scope of the claims 120 may occur to persons skilled in the art.

It is claimed and desired to secure by Letters Patent:

1. A motor rotor vane the trailing edge 125 of the working face of which is abruptly chamfered.

2. A motor rotor vane having abruptly intersecting working faces against which the same fluid acts successively.

3. A motor rotor vane having a substantially radial abruptly beveled discharge 130

- edge viewable from the fluid admission side of the vane.
4. A motor rotor vane having an abruptly beveled discharge edge viewable from the fluid admission side and in the direction of movement of the vane.
5. A motor rotor having vanes the trailing edge of the working face of each of which is abruptly chamfered.
- 10 6. An axial flow motor rotor having vanes the discharge edge of the working face of each of which is abruptly chamfered.
- 15 7. A motor rotor having vanes the trailing edge of the working face of each of which has an abrupt chamfer viewable from the inlet side of the rotor.
- 20 8. An axial flow motor rotor having substantially radial vanes the trailing discharge edge of the working face of each of which has an abrupt chamfer viewable from the inlet side of the rotor.
- 25 9. An axial flow motor rotor having substantially radial vanes the discharge edge of each of which is abruptly beveled viewable from the inlet side and in the direction of rotation of the rotor.
- 30 10. An axial flow motor rotor having vanes each of which is provided with abruptly intersecting working faces viewable from the inlet side of the rotor and against which the same fluid acts successively.
- 35 11. A motor rotor adapted for operation at high specific speed and comprising a hub and vanes associated with said hub, the area of said vanes projected upon a plane perpendicular to the rotor axis being less than the area of the annulus between the circles bounding the ends of said vanes, and the discharge edges of the working faces of said vanes being abruptly beveled.
12. A motor rotor adapted for operation at high specific speed and comprising a hub and vanes associated with said hub, the area of said vanes viewed in the direction of flow of the fluid, being less than the area of the annulus between the circles bounding the ends of said vanes, and the discharge edges of the working faces of said vanes being abruptly chamfered. 45
13. An axial flow motor rotor comprising a plurality of vanes, said rotor having spaces between the successive vanes as viewed in the direction of the rotor axis, and the discharge edges of said vanes having abrupt chamfers visible from the inlet side of the rotor. 50
14. A hydraulic turbine rotor comprising successive vanes forming a working passage which is locally abruptly constricted between the inlet and discharge edges of the vanes, said constriction being located closely adjacent to the rotor discharge. 55
15. A hydraulic turbine rotor comprising successive vanes forming a working passage having minimum transverse cross-sectional area between the inlet and discharge edges of the vanes, said portion of minimum transverse cross sectional area being located closely adjacent to the rotor discharge. 60
16. A hydraulic axial flow turbine rotor comprising successive substantially radial vanes forming a working fluid passage having minimum cross-sectional area measured in a plane perpendicular to the rotor axis, located intermediate the ends of said vanes and closely adjacent to the rotor discharge. 65
